Primary Examiner — Cynthia Ramirez(74) *Attorney, Agent, or Firm* — Brooks Kushman P.C.(57) **CLAIM**

The ornamental design for a screed, as shown and described.

DESCRIPTION

FIG. 1 shows a view onto the front side of a screed; FIG. 2 shows a view onto the left side of the screed of FIG. 1;

FIG. 3 shows a view onto the rear side of the screed of FIG. 1; FIG. 4 shows a view onto the right side of the screed of FIG. 1;

FIG. 5 shows a view onto the top side of the screed of FIG. 1; FIG. 6 shows a perspective view onto the rear side, right side and top side of the screed of FIG. 1; and,

FIG. 7 shows a further perspective view onto the front side, left side and top side of the screed of FIG. 1.
